Inventor:

G. F. Green

United States Patent Office.

G. F. GREEN, OF KALAMAZOO, MICHIGAN.

Letters Patent No. 98,864, dated January 18, 1870.

IMPROVEMENT IN UNIVERSAL-GEARED JOINTS

The Schedule referred to in these Letters Patent and making part of the same.

To all whom it may concern:

Be it known that I, G. F. GREEN, of Kalamazoo, in the county of Kalamazoo, and State of Michigan, have invented a new and improved Universal-Geared Joint; and I do hereby declare that the following is a full, clear, and exact description thereof, reference being had to the accompanying drawings, making a part of this specification.

Figure 1 is a perspective view of the geared joint. Figure 2 is a detached view of gear, sleeve, and annular segment.

Figure 3 is a similar view of gear, segment-guide, shaft, and set-screw.

Similar letters of reference indicate corresponding parts in the several figures.

The nature of my invention consists in so forming the teeth on two gear-wheels, that when properly set and held in position, by means of an annular segment, as will be hereafter described, they will move together freely at any desired angle.

The object of my invention is to construct a universal joint which will be capable of transmitting motion from a driving-shaft, in any combination of machinery, at any desired angle, and which may either be set and held in any position, or allowed to change the angle while in motion, as the case may require.

It may be used on the tumbling-rod of a threshing-machine, and also in a bit-brace or drill-stock, for boring or drilling at any angle, and for all other purposes where such a joint may be found useful.

To enable others skilled in the art to understand and construct my invention, I will describe its construction and operation.

Fig. 1. H H represent two gear-wheels, the teeth of which are like common spur-gear, with the exception of the peculiar shape. They project on one end so as to form a half circle, equal in diameter to the depth of the tooth, and are tapered toward the opposite end of the gear, nearly to the base of the tooth.

A is the sleeve, or tubular bearing, in which the shaft of one of the gear-wheels revolves.

B is an annular segment, firmly attached to the sleeve A.

E is the sleeve in which the driving-shaft G revolves.

To the under side of E is attached a guide, F, with a chamber turned in it, fitting closely to the segment B, which is set in such a position that its centre is located in the pitch-line at the point of contact of the gears H H, thereby permitting the gears to run freely together, at any angle within a half circle.

The gears H H are held in any desired position by the set screw C pressing segment B.

Claim.

I claim, as my invention—

The gear-wheels H H, constructed as described, in combination with the segment B and set-screw C, the centre of which segment is located in the pitch-line and point of contact of said gears, as and for the purpose set forth.

G. F. GREEN.
